UNITED STATES PATENT OFFICE.

EDWARD A. GEHRKE, OF LINCOLN, NEBRASKA.

AUTOMATIC FIRE-ALARM.

1,093,395.

Specification of Letters Patent. Patented Apr. 14, 1914.

Application filed March 22, 1913. Serial No. 756,186.

To all whom it may concern:

Be it known that I, EDWARD A. GEHRKE, a citizen of the United States, residing at Lincoln, in the county of Lancaster and State of Nebraska, have invented certain new and useful Improvements in Automatic Fire-Alarms, of which the following is a specification, reference being had therein to the accompanying drawing.

This invention relates to a fire alarm, and has special reference to a device which is provided with thermostatic means for turning in the alarm when the heat reaches a predetermined point.

Another object of this invention is the production of a simple means whereby an alarm may be turned in by hand, and which is used in combination with means for preventing the several parts from becoming injured.

With these and other objects in view, this invention consists of certain novel combinations, constructions and arrangements of parts as will be hereinafter fully described and claimed.

In the accompanying drawings: Figure 1 is a perspective view of the fire alarm. Fig. 2 is a central longitudinal sectional view of the device. Fig. 3 is a top plan view of the base plate, the spring and contact arm. Fig. 4 is a section taken on line 4—4 of Fig. 2, looking in the direction of the arrow. Fig. 5 is a perspective view of a portion of the base plate. Fig. 6 is a plan view of the blank from which the spring and contact arm are made. Fig. 7 is a perspective view of the contact post.

Referring to the accompanying drawings by numerals, 1 designates the base plate which is provided with laterally-bent flanges 2. This base plate 1 is provided with a binding post 3 which is held upon the plate by means of a nut 4. The upper portion of this binding post 3 is provided with a slot 5 in which the thermostatic strip 6 is positioned. This thermostatic strip 6 is held in place by means of a screw 7. The outer portion of the thermostatic strip is provided with a laterally-bent contact arm 8, which terminates in a twisted portion 9 for forming an efficient contact member. Intermediate the ends of the arm 8 there is provided an indicating arm 10 which is provided with a suitable operating member 11. The plate is also provided with a contact post 12 having a pair of arms 13 and an

aperture 14. A contact screw 15 is positioned between the arms and is held in engagement by means of a binding screw 16, while the post is held in position by means of the nuts 12'. 60

When the heat within a room reaches a predetermined point the effect upon the thermostatic strip will cause the same to expand, whereby the arm 8 will be moved 65 to one side, at which time the twisted portion 9 will come in engagement with the contact screw 15, and the circuit will close for turning in an alarm. It will, of course, be obvious that the lower portions of the 70 binding and contact posts are provided with electric means for forming a circuit.

In order to inclose the several parts of this device there is provided a suitable hood 17 having a transverse slot 18 through which 75 the arm 10 is adapted to pass. A spring finger 19 is positioned upon the side of this hood 17, which carries, at its upper end, a transverse bar 20. As this finger 19 is secured at one end only to the side of the hood, 80 there will be allowed considerable play when the member 11 is brought into engagement with the bar 20, whereby when an alarm is turned in by hand, there will be no danger of breaking the spring finger from the side 85 of the casing. By means of this spring finger 19 and the bar 20 a person will know which way to pull the member 11 for manually operating the device as the finger and bar will serve as an indicating member. 90

The flanges 2 are provided with apertures 21 adapted to register with the apertures 22 formed in the hood, whereby bolts 23 may be passed therethrough for holding the plate in engagement with the hood. It will be 95 further seen that the hood and plate are each provided with a plurality of apertures 24, which are adapted to allow the heat to have free access to the interior of the hood for expanding the thermostatic strip 6. It 100 will also be seen that the binding post 3 is provided with an insulated washer 25 and the insulated block 26' which are held in position by means of the flange 26 and the nut 4 whereby the post will be supported upon the base without causing a short circuit by coming into contact with said base. 105

From the foregoing description, it will be seen that a simple device has been produced, which will efficiently close a circuit for turning in an alarm when the heat reaches a predetermined point, or by use of which an 110

alarm may be turned in by manually operating the device.

Having thus described my invention, what I claim is:

- 5 A fire alarm comprising a base plate, a hood carried by said base plate, a binding post carried by said base plate, a thermostatic strip carried by said binding post, said thermostatic strip provided with a 10 laterally-bent contact arm, said arm terminating in a twisted portion, said arm also provided with a vertically-extending indicating arm, said hood provided with a transverse slot, said indicating arm passing 15 through said slot and having, at its upper end, a horizontal operating member, a spring finger carried by the side of said hood, adjacent said slot, said spring finger provided with a transverse bar, a contact 20 post carried by said plate and provided with an adjustable contact screw, said hood

and plate provided with a plurality of openings, whereby the heat may be allowed to circulate within said hood for expanding said thermostatic strip so as to move said 25 twisted portion and said contact arm in engagement with said contact screw, electric means connected to the lower portions of said posts for forming a circuit when said contact arm engages said contact post, and 30 said spring finger adapted to give slightly when said operating member strikes the same when the circuit is closed by hand, whereby said spring finger will be prevented from breaking off the side of the 35 hood.

In testimony whereof I hereunto affix my signature in presence of two witnesses.

EDWARD A. GEHRKE.
